MAGNETIC DRILL SUPPORT

Eugene W. Buck, Campbell, Calif.

Application January 20, 1956, Serial No. 39,860

Term of patent 14 years

(Cl. D63—1)

FIG. 1

Figure 1 is a side elevation view of a magnetic drill support embodying my new design with the electric drill, and extension cord illustrated in dotted lines for purposes of illustration only;

Figure 2 is an elevational view of the drill support taken from the left of Figure 1, with the drill and extension cord omitted; and

Figure 3 is a top plan view of Figure 2.

The dominant features of the design reside in the portions shown in full lines.

I claim:

The ornamental design for a magnetic drill support, as shown and described.
